PATENTED SEPT. 13, 1904.

J. W. MAY.

ADVERTISING DISPLAY MEANS.

APPLICATION FILED AUG. 24, 1903.

NO MODEL.

UNITED STATES PATENT OFFICE.

JEROME W. MAY, OF NEW YORK, N. Y.

ADVERTISING DISPLAY MEANS.

SPECIFICATION forming part of Letters Patent No. 769,868, dated September 13, 1904.

Application filed August 24, 1903. Serial No. 170,556. (No model.)

To all whom it may concern:

Be it known that I, JEROME W. MAY, residing in the borough of Manhattan, city and State of New York, have invented certain new and 5 useful Improvements in Advertising Display Means, of which the following is a specification.

My invention in advertising display means relates to that class of advertising devices 10 wherein an article of public utility is disposed as a feature of attraction, whereby the attention of the public is drawn to the advertising matter usually displayed in the form of cards representing the various branches of trade to 15 which it is desired to call attention, and the whole being contained within a suitable framework or inclosure, so as to constitute a unit.

The object of my invention in this connection is to provide an article of utility, preferably a toilet article—such, for example, as a 20 mirror—as a chief feature of attraction in directing the attention toward the advertising matter in such places as theaters, concert-halls, auditoriums, and the like by affixing 25 the advertising matter, together with the mirror, on the backs of chairs or seats, so that the occupants of a series of chairs or seats may become availed of the utility of the mirrors located in the backs of the respective chairs 30 or seats ahead of them.

The chief feature characteristic of my invention lies in the manner whereby the framework which carries the mirror, together with the advertising matter, is disposed on the back 35 of the chair so as to admit of the mirror being brought and set into a desired position for use. In carrying this feature of my invention into practice I have arranged a mirror centrally located with respect to the display of the advertising matter carried in a suitable framework of wood, light metal, or other suitable 40 material. I have provided the upper edge of the frame where it adjoins the seat-back with a special hinge, adapted to the purpose of my invention and which forms part thereof, by 45 which the said frame is secured to the seat-back and arranged and constructed, as will be hereinafter more fully described, so as to permit the framework carrying the advertising matter and mirror to be compactly arranged

relative to the seat-back when said framework shall not be in a position more convenient for the user. By this feature of my invention the necessity for having to return the display means to its original position is obviated, 55 which otherwise would be attended with the liability of catching or tearing the garments of the occupant of a preceding seat, more especially while entering or leaving the same, or the display-frame from the back of the 60 chair.

Still another object of my invention is to provide such advertising display means with an additional feature of utility, and in this connection I prefer to provide at the upper 65 edge of the frame an adjustable spring-actuated arm, disposed as a hat-carrier, and construct it in a manner so as to be in accordance with the aforesaid provisions of my invention, whereby the said arm shall be eliminated when 70 not in use, obviating its being obstructive, all of which will be hereinafter more fully described in the specification, and illustrated in the drawings hereto attached, and the distinctive features of invention more fully pointed 75 out in the claims.

In the drawings, Figure 1 is a perspective view of a chair, illustrating the manner of attaching my improved advertising display means and also showing the same in a partly-raised position, as when being used. Fig. 2 is a sectional elevational view of a portion of a chair-back and somewhat different construction of mechanism which operates the swinging frame. In this view the swinging frame 85 is shown as a longitudinal section taken centrally through the attachment. Fig. 3 is a like view to that of Fig. 2 with the swinging frame closed upon the back of a chair. Fig. 4 is a sectional elevational view of the 90 upper portion of a chair-back embodying my invention, showing the operating parts, some of these parts being shown in the perspective, Fig. 1. Fig. 5 is a view of the frame-operating mechanism shown in Fig. 4, the frame 95 being removed. Fig. 6 is a plan view of the parts shown in Fig. 4, the frame, however, being in a flat position. Fig. 7 is a detail longitudinal sectional view illustrating a still further modification of the swinging mechanism. 100

Similar reference characters are employed to designate corresponding parts throughout the several figures of drawings.

As illustrated in Fig. 1, a conspicuous feature of the device is presented by a frame A, pivotally connected at the rear of a chair-back B, near the upper edge thereof. This frame A has its exposed face divided by suitable strips a, forming divisions a' for receiving advertising matter, and a centrally-located division a² for containing a mirror in order to impart a quality of personal utility to the device. The frame A is provided at that side immediately opposite the chair-back with upper ears a³, which are transversely perforated for the reception and securement of the ends of pins b, which revolubly bear in rearwardly-projecting ears b', rigidly secured to the chair-back. The inner ends of the pins b have secured thereto blocks b², each provided with two intersecting cam-faces b³. Leaf-springs c are also appropriately secured to the chair-back and each has its free upper end extending in such position that it will bear full upon either cam-face of the contiguous block b², according to the position in which the latter is turned.

From the description thus far it will be readily comprehended that with the frame secured to the back of a chair as explained it may be moved to lie flat against the same or be raised to occupy the inside position (illustrated in Fig. 1,) in which latter condition a person seated at the rear of the chair will be enabled to not only conveniently discern the advertising matter carried by the frame, but utilize the mirror therein. The character of the cam-blocks with the particular arrangement of leaf-springs provides for positively retaining the frame in either its depending or inclined positions and insures the final movement in approaching either position by the action of the free ends of the springs after the cam-blocks have passed their dead-centers, which is the point of intersection of the two cam-faces.

The importance and utility of the invention will be most appreciated when considered in connection with its application to the backs of chairs in theaters and similar public edifices for accommodating seated audiences. With the frames on the backs of the chairs, as immediately before referred to, an extensive advertising capacity is provided, while the mirror feature of the improvement greatly enhances its utility as well as attractiveness.

I do not desire to be understood as limiting myself to any particular means for coacting with the pivotal portions of the frame, the desideratum being, however, that such means should materially aid in the movement of said frame in assuming either its flat or inclined positions and serve to definitely retain the frame in either. Thus in Figs. 2 and 3 I have represented a cylinder C' as being pivotally

connected at its lower end to a bracket C², projecting from the casting secured to the chair-back, a plunger c² being movably carried within the cylinder by a rod c', the upper end of which is eccentrically connected to the ears a⁴ on the back of the frame A'. In this arrangement the lowering movement of said frame will result successively in slight upward and descending movements of the plunger, such movements being occasioned by the passage of the rod connection with the ears from a position at one side of the pivots b to a position at the other side thereof. Manifestly the lifting of the frame to an inclined position will cause a change in the position of the rod connection to one at the other side of the ear-pivots, the same successive upward and descending movements of the plunger taking place. While undergoing the descending and ascending movements referred to an expanding spring c³, interposed between the upper cylinder-head and the plunger, respectively, will be compressed, and as soon as the rod connection passes beyond the dead-center position said spring will react to depress the plunger for automatically completing the lowering or raising movement of the frame, as the case may be, and coact to retain such frame in either of said positions. A short expanding spring c⁴ of somewhat less resiliency than the spring c³ is interposed between the plunger and lower head of the cylinder and serves to cushion said plunger during its downward movements.

In Fig. 7 I have illustrated an arrangement operating somewhat after the manner of the spring provision employed in connection with the blade of a penknife. In the construction in the last-mentioned figure a casting C² is secured to the back B² of the chair and has an upper ear b⁴, in which revolubly bears a pin a⁶, rigidly carried by the ear a⁷ on the frame A³. This latter ear a⁷ has two cam-faces for coaction with the upper free end of a strong thick spring C³, which is intermediately held in position by being passed downwardly through a loop c⁷, integral with the casting, while the lower end is introduced within a recess in an ear c⁹, the latter being integral with the lower end of the casting, such recess in the ear c⁹ being undercut to form a lug c⁸, which is engaged by the lower hooked end of the spring, the recess in the ear c⁹ being sufficiently ample to permit the end of the rod after insertion in said recess to be moved laterally in order to engage the hook with the under side of the lug. The operation of this form of the invention will be obvious. The raising or lowering of the frame A³ will cause the spring C³ to be compressed toward the seat-back until the cam-point of each of the ears a⁷ passes the dead-point, whereupon the free ends of the springs will act to aid in bringing the frame to its final position in either movement thereof.

From the foregoing description it will be appreciated that the attachment embodying my invention is comparatively simple, conveniently applied, and highly serviceable, besides furnishing an advertising medium capable of proving extremely lucrative.

Having now described my invention, what I claim as new, and desire to secure by Letters Patent, is—

- 10 1. The within-described means comprising a frame having at one side a display-surface, devices below the upper edge of the frame, at its reverse side for the attachment of said frame to the rear of a seat-back, said devices including ears connected to the frame and swinging on suitable pivots, together with provision disposed at the reverse side of the frame, extending in a plane below the ears and exerting a force to swing and retain said frame in a raised or lowered position when at either side of a central position.

- 15 2. The within-described means comprising a frame having at one side a display-surface, devices below the upper edge of the frame, at its reverse side for the attachment of said frame to the rear of a seat-back, said devices including ears connected to the frame and swinging on suitable pivots, together with

spring provision disposed at the reverse side of the frame, extending in a plane below the ears and exerting a force to swing and yieldingly retain said frame in a raised or lowered position when at either side of a central position.

3. The within-described means comprising a frame having at one side a display-surface, devices below the upper edge of the frame, at its reverse side for the attachment of said frame to the rear of a seat-back, said devices including pivotal ears provided with cam-faces disposed at an angle with respect to each other, and leaf-springs coactive with the ears to bear alternately on the cam-faces thereof, and adapted to exert a force to positively swing said frame to a raised or lowered position when at either side of a central position, said springs when bearing fully against either of the faces serving to maintain said frame in either a raised or lowered position.

In testimony whereof I have signed my name to this specification in the presence of two subscribing witnesses.
